UNITED STATES PATENT OFFICE.

MICHAEL J. MILMOE, OF CHICAGO, ILLINOIS, ASSIGNOR TO F. B. REDINGTON COMPANY, OF CHICAGO, ILLINOIS, A CORPORATION OF ILLINOIS.

FEEDING MECHANISM.

Application filed November 4, 1925. Serial No. 66,778.

- This invention relates to mechanism for feeding packages or thin articles from a magazine and arranging them in sets or bundles to be wrapped or otherwise disposed of.
- 5 The object of the invention is to provide a mechanism of the class named which shall be automatic and accurate and which shall be of improved construction and operation.
- The invention is exemplified in the combination and arrangement of parts shown in the accompanying drawings and described in the following specification, and it is more particularly pointed out in the appended claims.
- 15 In the drawings—
- Fig. 1 is an elevation of a portion of a wrapping machine having one embodiment of the present invention applied thereto;
- Fig. 2 is a front elevation of the mechanism shown in Fig. 1, with parts omitted;
- Fig. 3 is a front elevation of the feeding mechanism, with parts in section;
- Fig. 4 is a fragmentary sectional view substantially on line 4—4 of Fig. 2;
- 25 Fig. 5 is a view similar to Fig. 4 showing the parts in a different position;
- Fig. 6 is a view looking in the direction of the arrow 6 in Fig. 5; and
- Fig. 7 is a horizontal section substantially on line 7—7 of Fig. 4.
- In the embodiment shown in the drawings, the feeding mechanism is shown as applied to a machine for placing a number of wrapped razor blades together in a package.
- 35 The blades in their individual wrappings are designated by the numeral 10. They are arranged in stacks in a hopper 11 consisting of an inclined back plate 12 and longitudinal ribs 13 projecting upwardly from the top 40 of the back plate. The blades are stacked upon one another in the inclined troughs or grooves between the ribs 13. As shown in Fig. 1, the hopper 11 is supported on the frame 14 of the packaging machine by means 45 of a bracket 15. A second bracket 16, shown in Fig. 3, supports the hopper 11 at the side opposite the bracket 15. A shaft 17 is journaled in bearings 18 and 19 supported by brackets 20 and 21, the bracket 20 being carried on the support 15, while the bracket 21 projects downwardly from the hopper 11. The shaft 17 is centrally bored to provide an internal cylindrical opening 22 extending inwardly from the left-hand end of the shaft, 55 as viewed in Fig. 3, to a point adjacent the bearing 18. A tube 24 slidably engages the recess 22 and is provided with a support 25 for holding the outer end of the tube in registration with the opening 22. The shaft 17 has a drum 26 secured thereto and arranged to 60 rotate therewith. The drum is provided with a series of circumferential flanges 27, the peripheries of which are arranged in registration with the lower ends of the grooves or troughs between the ribs 13 on the hopper 65 11. The drum 26 is provided with internal chambers 28 and 29 which are separated by a partition wall 30. For convenience of manufacture the drum may be made in separate sections and the sections fixed together, the 70 ends of the drum being closed to seal the chambers 28 and 29. Radiating from the chambers 28 and 29 and disposed within the circumferential flanges 27 is a series of air ducts 31, there being four air ducts in the first and third flange starting from the left in Fig. 3, and six air ducts in the second and fourth flange, the six air ducts being arranged in sets of three, as shown in Fig. 4. The air ducts in the different flanges are arranged 75 in registration with one another and the ducts are bored longitudinally to provide openings for slide valves 32 intersecting the air ducts 31. Adjacent each of the air ducts 31 is a vent 33 which is connected to the air duct 31 by a port 34 in the slide valve when the valve is in the position shown in the lower portion of Fig. 3. When the valves are in the opposite position shown at the upper portion of Fig. 3 peripheral grooves 35 formed 80 in the valves connect the inner and outer ends of the air ducts and at the same time the air ducts are disconnected from the ports 34 leading to atmosphere. When the valves are in the position shown in the lower portion 85 of Fig. 3 the air ducts 31 are closed.
- The chambers 28 and 29 are connected to the interior 22 of the shaft 17 by perforations 36. The perforations in the chamber 28 may be closed by sliding the tube 24 to the right, as 90 viewed in Fig. 3. The tube 24 is connected to an exhaust pump, not shown in the drawings, so that when the tube is in the position shown in Fig. 3 air will be exhausted from both chambers 28 and 29. When the tube is slid 95 inwardly past the opening 36 the portion of the drum connected with the chamber 28 will be placed out of operation, while the air ducts connected with the chamber 29 will continue to operate.

The shaft 17 is driven by means of a sprocket wheel 37 mounted at one end thereof and connected by a chain 38 with a sprocket wheel 39 on a shaft 40 journaled in the frame 14. 5 The shaft 40 is connected by gears 41 with the main drive shaft 42. A take-up pulley 43 may be provided for regulating the tension in the chain 38. A conveyer chain 44 travels on ways 45 arranged below the drum 26. 10 The chain 44 is provided with links having upwardly extending teeth 47 providing pockets 48 for receiving the articles from the flanges 27. The conveyer 44 is moved intermittently by a ratchet wheel 49 operated by 15 a pawl 50 carried on the end of a bar 51. The bar 51 is provided with a cam roller 52 which meshes with a groove 53 in a cam 54 secured to the main drive shaft 42. The cam groove 53 is shaped to permit the conveyer to 20 remain stationary during a quarter of a revolution of the drum 26. During the next quarter revolution the conveyer will be moved forwardly the length of one link of the conveyer chain. During the next quarter of a revolution 25 the conveyer will remain stationary again and will be moved the distance of another link during the fourth quarter of a revolution. While the conveyer is stationary the three air ducts on the second and fourth flange from 30 the left in Fig. 3 arranged in one quarter of the drum will be brought successively into registration with a pocket in the conveyer and will each discharge a razor blade in the pocket beneath it. At the same time the two corresponding air ducts in the first and third flange will be brought into registration with 35 the conveyer pockets beneath and discharge two blades in these pockets. It will thus be seen that when a particular pocket has passed 40 all four of the flanges the pocket will have received in all ten blades, which is the number commonly placed in a package. A fifth flange 55 may be provided on the drum 26 for depositing a cardboard strip or other identification or advertising article on top of the stack of blades. The mechanism for feeding 45 the cardboard strip is not shown in the drawings as the particular feeding mechanism for this purpose is not a part of the present invention.

At the outer end of each of the air ports 31 the flanges 27 are provided with flattened portions 56 for receiving the blades 10. The blades 10 are periodically raised in their magazines out of contact with the flanges 27 by fingers or blades 57 which are secured to a bar 58 pivotally mounted at 59. There is one finger 57 at each side of each of the flanges 27 and disposed beneath the ends of the blades 60, as shown in Fig. 6. The fingers 57 are limited in their downward movement by stops 60 so that when the fingers are in their lowermost position the blades 10 will be permitted to slide downwardly to permit the lowermost 65 blade to engage the periphery of the flange

27. A cam projection 61 is provided on the bracket member 21 to move the slide valve 32 to the right, as shown at the top of Fig. 3, when the corresponding air ducts 31 are brought into registration with the magazine. 70 At this time the fingers 57 will be in their lowered position, as shown in Fig. 4, so that the lowermost blade 10 will rest upon the periphery of the flange 27. The suction in the chambers 28 and 29 will cause the blades 75 to adhere to the periphery of the flanges 27 and be withdrawn from the stacks in the magazine. In order to facilitate removal of the lowermost blade it is desirable to prevent the weight of the entire stack from resting on the 80 blade to be withdrawn. This result is secured by means of arms 62 pivoted at 63 on the magazine 11. Each arm carries a plate 64 at its lower end which projects at opposite sides of the arm 62 and overlies the blades 10 in 85 the magazines at each side of the arm 62. There is one arm 62 for each pair of magazines. The arm 62 is provided with an angularly disposed extension 65, the adjacent ends of the arm and extension being spaced from 90 each other and connected by plates 66 secured at each side of the arm 62. This provides an opening 67 between the arm 62 and its extension 65 through which a threaded rod 68 projects, the rod being fixed to the rib 13 beneath 95 the arm 62.

A plate 69 is provided with a perforation through which the rod 68 extends, the plate resting on top of the bar 62 and being pressed against the bar by a spring 70 surrounding 100 the rod 68. Lock nuts 71 are provided for adjusting the compression in the spring 70. The spring ordinarily presses the plate 64 against the ends of the blades 10 to hold them in place in the magazine. A pin 72 extends 105 transversely of the extension 66 and carries at its opposite ends detents 73 which bear on the peripheries of the adjacent flanges 27. The detents 73 are resiliently pressed against the flanges by engagement with the spring-pressed plate 69. The flanges 27 are provided with pins 74 arranged to engage the bottom edges of the extension 65 and lift the bar 62 against the compression of the spring 70. The bar 62 is lifted after each removal of a 110 blade from the bottom of the stack. Rollers 75 are carried on the outer face of the endmost flange 27 in position to engage the end finger 57 and raise all of the fingers 57 simultaneously at the time that the bars 62 are lifted by the pin 74. This will raise the stacks of blades in their magazines and while they are thus lifted the pin 74 will release the bars 62 and the plates 64 will be returned into engagement with the blades. The plates 64 are provided with extensions 76 which engage all but a small number of the blades at the bottom of the stack. These blades, as shown in Fig. 4, will be permitted to drop down against the periphery of the flanges 27 when the fingers 57 115

120

125

130

are released so that the lowermost blade may be easily extracted from the magazine without the resistance which would be offered if the entire weight of the stack rested upon the 5 blades. If more than a single blade is withdrawn it will be intercepted by the detent 73 as the flange 27 rotates. If it should happen that a blade is not in exact registration with the flat portion on the periphery of the disc 10 but extends rearwardly beyond the flat portion, the end of the blade will project above the outer periphery of the disc. This will not prevent the blade from passing beneath the detent 73, however, since the forward end of 15 the blade will pass beneath the detent and the detent will yield to permit the rear end to pass due to the resiliency of the spring 70. The spring 70 does not press the detent 73 inwardly beyond the periphery of the flange 27 20 and the flat portion 56 on the periphery of the flange will permit the blades 10 to pass the detent 73 when in proper registration with the flat portion without exerting pressure on the blades. If a blade is attached to the disc in 25 position to project forwardly beyond the flat portion it will be moved back into proper registration by the detent 73. The blades are held against the peripheries of the flanges until they are brought into registration with the 30 conveyer below the drum.

Disposed in the grooves between the flanges 27 at the bottom of the drum are guide fingers 77 supported from the ways 45 by a bar 78. The fingers 77 have beveled portions 79 at 35 their forward ends to direct the blades into registration with the pockets in the conveyer 44. The fingers 77 have shoulders 80 for engaging the ends of the blade and causing them to drop from the flanges 27 into the conveyer 40 pockets. At the same time that the blades engage the shoulders 80 the end of the slide valve 32 engages a cam surface 81 projecting from the bracket 20 sliding the valve to the left, as viewed in Fig. 3, so as to close the air 45 ducts 31 and connect the outer ends of the air ducts with the atmosphere. This releases the suction in the air duct and permits the blade to drop freely into the conveyer pocket. The parts are positioned to release the blade before 50 it is moved to the extreme end of the pocket as otherwise there would be danger that the end of the blade might rest against the bar 78 instead of falling to a flat position in the bottom of the pocket. A guide bar 82 is arranged at 55 the front side of the pocket and spaced outwardly a short distance from the conveyer, as shown in Fig. 4. This bar has an inclined portion approaching the conveyer so that the blades are moved inwardly by the beveled inner face of the bar as the conveyer moves toward its discharge end. The blades are discharged from the conveyer to suitable packaging mechanism which forms no part of the 60 present invention.

It will be seen that the mechanism automatically extracts the blades from the hoppers and deposits a definite number in the pockets of the conveyer. If the tube 24 is in the position shown in Fig. 3 each pocket will receive ten blades, but if the packages of five are desired the tube may be moved inwardly to disconnect the chamber 28 and the machine will then operate to deposit five blades only in each pocket. 65

I claim:—

1. In combination, an inclined magazine for supporting a series of flat articles on top of one another, a rotary suction device having a suction opening therein arranged adjacent the bottom of said series, the bottom 80 of said series being disposed adjacent the path of rotary movement of said device at one side of the uppermost position of said device and means for rotating said suction device to move said opening upwardly past the bottom of 85 said series to extract the lowermost article from said series.

2. In combination, a magazine for containing articles to be fed, means for extracting articles at the lower end of said magazine, 90 means for lifting all the articles in said magazine, and frictional engaging means for retaining a portion of the articles in raised position but permitting return of the lowermost of said articles to a lowered position to 95 be engaged by said extracting means at the time said article is extracted from the lower end of said magazine.

3. In combination, a magazine for supporting articles to be fed, and a member mounted stationary with respect to said magazine for frictionally engaging the articles in said magazine, said engaging means being operative to support the upper articles but inoperative to support the lowermost articles 100 to permit the lowermost articles in said magazine to move downwardly while retaining the upper articles in position. 105

4. In combination, an inclined magazine for supporting articles to be fed, a contact member extending along the side of said magazine for engaging said articles, means for extracting articles from the bottom of said magazine, and means for periodically lifting said contact member to permit said 110 articles to be adjusted in said magazine. 115

5. In combination, an inclined magazine for articles to be fed, a contact member extending along the upper side of said magazine for engaging the articles in said magazine, means for periodically lifting said contact member out of engagement with said articles, and means for raising said articles in said magazine while said contact member is lifted, said contact member being permitted to re-engage said articles while lifted to retain 120 said articles in their lifted position, the lowermost articles in said magazine being below 125

- said contact member so that they are free to move downwardly while the upper articles are supported in elevated position.
6. In combination, a magazine for supporting articles on top of one another, means for extracting articles from the lower end of said magazine, and means for lifting the articles in said magazine and frictionally retaining the upper ones of said articles in raised position for relieving the lowermost articles in said magazine from the weight of the upper articles therein to permit easy extraction of an article from the lower end of said magazine.
- 15 7. The combination with a magazine for supporting a stack of articles, of a rotary suction member for extracting articles from the lower end of said magazine, and frictional means extending along the upper portion of said magazine but terminating above the lowermost article therein for supporting the upper articles in said magazine above the lowermost articles therein to facilitate easy removal of the lowermost articles by said 25 rotary suction member.
8. In combination, a magazine for supporting a stack of articles, a suction member movable past the bottom of said magazine in a direction transverse to the axis of said magazine to extract articles from the bottom of said magazine, means for periodically raising all the articles in said magazine, and means for sustaining the upper articles in said magazine in their raised position while the lowermost articles therein are returned to the bottom of said magazine to permit extraction of the lowermost article by said suction member while said article is free from the weight of the stack in said magazine.
- 40 9. In combination, an inclined magazine for supporting a stack of articles, a rotary suction member movable in an upward direction past the lower end of said magazine, means for periodically raising the articles in said magazine, and a contact member for engaging the articles in said magazine to retain the upper articles therein in their raised position while permitting a limited number of the lowermost articles to move downwardly to the bottom of said magazine to permit the lowermost article to be extracted by said rotary suction member while free from the weight of the stack of articles in said magazine.
- 55 10. In combination, a magazine for supporting a stack of articles on top of one another, a spring-pressed contact member for engaging said articles to prevent downward movement thereof in said magazine, a rotary suction device for extracting articles from the lower end of said magazine, and means on said suction device for releasing said contact member in timed relation to the movement of said suction device.
- 60 11. In combination, an inclined magazine for supporting articles to be fed, a rotary suction device having the periphery thereof disposed adjacent the lower end of said magazine, a spring-pressed contact member for engaging the articles in said magazine to hold said articles against downward movement in said magazine, said contact member having an extension disposed adjacent the path of said suction device, and means on said suction device for engaging said extension to lift said contact member in timed relation to the movement of said suction device.
12. In combination, a magazine for supporting articles to be fed, a rotary member disposed adjacent the bottom of said magazine for extracting articles therefrom, a lifter arranged to engage the articles in said magazine, means on said rotary member for periodically engaging said lifter to raise the articles in said magazine, a contact device for engaging all but the lowermost articles in said magazine, and means on said rotary member for releasing said contact device during the operation of said lifter.
13. In combination, a magazine for supporting articles on top of one another, a rotary member for extracting articles from the bottom of said magazine, a lifter for raising the articles in said magazine, a contact device for holding all but the lowermost articles in said magazine from movement therein, and means controlled by said rotary member for operating said lifter and contact device in timed relation so that said contact device is released during the upward movement of said lifter but returned to engagement prior to the return movement of said lifter.
14. In combination, an inclined magazine having the top thereof open, a spring-pressed plate disposed above the top of said magazine for engaging the upper surfaces of articles therein, said magazine extending below the lower edge of said plate so that the lowermost articles in said magazine are free from said plate, means for extracting articles from the bottom of said magazine, and means operated by said extracting means for lifting said plate.
15. In combination, an inclined magazine having the top thereof open, a spring-pressed plate disposed above the top of said magazine for engaging the upper surfaces of articles therein, said magazine extending below the lower edge of said plate so that the lowermost articles in said magazine are free from said plate, means for extracting articles from the bottom of said magazine, means operated by said extracting means for lifting said plate, and means for raising said articles in said magazine while said plate is lifted.
16. In combination, a magazine for supporting a series of articles, a rotary suction device having a suction opening arranged to rotate adjacent the bottom of said magazine,

- and a detent for engaging said suction device to limit the number of articles extracted at one time from said magazine by said suction device.
- 5 17. In combination, a magazine for supporting a series of articles on top of one another, a rotary suction device having a suction opening therein arranged to rotate adjacent the bottom of said magazine for extracting articles from said magazine, and a spring-pressed detent arranged to engage said suction device at the side of said magazine where said suction device moves away from said magazine.
- 10 18. In combination, an inclined magazine having the upper face thereof open, a suction device having a suction opening therein arranged to move upwardly past the lower end of said magazine, and a spring-pressed detent arranged to engage said suction device adjacent the upper side of said magazine.
- 15 19. In combination, a magazine for supporting articles to be fed, a drum having a flattened portion on the periphery thereof arranged to move adjacent the endmost articles in said magazine, a detent for limiting the number of articles extracted from said magazine by said drum, and means for holding said detent against the cylindrical periphery of said drum but permitting said detent to clear the flattened portion of said drum.
- 20 20. In combination, a magazine for support a stack of articles on top of one another, a drum arranged to rotate adjacent the bottom end of said magazine, said drum having a flattened portion on the periphery thereof and a suction opening extending through said flattened portion, a detent for engaging said drum adjacent said magazine, and resilient means for pressing said detent against the cylindrical surface of said drum but permitting said detent to free said flattened portion so that articles held against said flattened portion will move readily beneath said detent.
- 25 21. In combination, in inclined magazine for supporting articles on top of one another, said magazine having the top face thereof open, a spring-pressed contact member for engaging the articles in said magazine, a lifter for raising the articles in said magazine, a drum arranged to rotate adjacent the lower end of said magazine, said drum having a flattened portion on the periphery thereof and a suction opening extending through said flattened portion, means on said drum for raising said contact member, means on said drum for operating said lifter while said contact member is raised, said contact member being arranged to re-engage said articles while lifted but leaving the lowermost articles free, and a spring-pressed detent for engaging the periphery of said drum to limit the number of articles extracted from said magazine by said drum, said detent being resiliently held against the cylindrical portion of the periph-
- ery of said drum but arranged to clear the flattened portion thereof to permit ready movement of an article held on said flattened portion past said detent.
22. Feeding mechanism comprising a suction member having a plurality of holding faces, and an exhaust device connectible with different numbers of said faces to vary the capacity of said feeding mechanism.
- 70 23. Feeding mechanism comprising a plurality of suction chambers, article holding faces separately connected with said chambers, and an exhaust device arranged to be connected with one or more of said chambers to vary the capacity of said feeding mechanism.
- 75 24. Feeding mechanism comprising a rotary suction device having a plurality of suction chambers therein, said suction device having separate article holding faces separately connected with said suction chambers, and adjustable means for exhausting air from one or more of said chambers.
- 80 25. Feeding mechanism comprising a rotary drum having internal chambers separated by a partition wall, article holding surfaces on the periphery of said drum connected with said chambers respectively, a hollow shaft on which said drum is mounted, and a suction device disposed in said shaft and movable therein to exhaust air from one or more of said chambers.
- 85 26. Article feeding mechanism comprising a hollow drum having a transverse partition therein and having air ducts extending from the interior of said drum to the periphery thereof at opposite sides of said partition, a hollow shaft for said drum, and a suction tube arranged to slide longitudinally in said shaft to exhaust air from said drum at one or both 90 sides of said partition.
- 95 27. Article feeding mechanism comprising a drum having circumferential flanges thereon, said drum being provided with a plurality of internal chambers having air ducts extending outwardly through said flanges to the peripheries thereof, a hollow shaft extending through the center of said drum and communicating with chambers therein, and an exhaust tube mounted to slide within said 100 hollow shaft into one position for closing the communication from one of said chambers to said exhaust tube and into another position for exhausting air from said chamber.
- 105 28. Feeding mechanism comprising a drum having internal chambers separated by a transverse partition, circumferential flanges on said drum having air ducts therein communicating with said chambers respectively, means for supporting articles adjacent the peripheries of said flanges, a hollow shaft for said drum having openings therein communicating with the chambers in said drum, and an exhaust tube slidably mounted in said 110 shaft and movable into position to close or 115
- 120 125 130

open the openings in said hollow shaft communicating with one of said chambers.

29. Feeding mechanism comprising a rotary suction device having a radial air duct therein, means connected with the interior of said suction device for exhausting air from said air duct, and a slide valve extending across said air duct and movable in the direction of the axis of said suction device for controlling the passage of air therethrough.

30. Feeding mechanism comprising a drum having an internal chamber therein, an air duct connecting said chamber with the periphery of said drum, means for exhausting air from said chamber, a valve for controlling the passage of air through said air duct, means for opening said valve to connect the open end of said air duct with said exhaust chamber when said open end is in one position, and means for shifting said valve to close the connection between said open end and said chamber and to connect said open end with atmosphere when said open end is in another position.

31. Feeding mechanism comprising a rotary suction device having a plurality of air ducts therein spaced from one another in the direction of the axis of said suction device, and a common valve disposed eccentrically of said rotary suction device for controlling said air ducts.

32. Feeding mechanism comprising a rotary drum having a suction chamber therein and a plurality of air ducts connecting said chamber with the periphery of said drum, a valve extending longitudinally of said drum eccentrically thereof and intersecting said air ducts, and means for sliding said valve longitudinally to control the passage of air through said air ducts.

33. Feeding mechanism comprising a rotary drum having a plurality of suction chambers therein, an exhaust device adjustable for exhausting air from one or more of said chambers, said drum having air ducts therein connecting said chambers with the periphery of said drum, means for supplying articles to the periphery of said drum, a slide valve intersecting said air ducts, and cam devices at opposite ends of said drum for alternately moving said slide valve in opposite directions.

34. Feeding mechanism comprising a rotary drum having an air duct provided with a peripheral opening, an exhaust device connected with the inner end of said air duct, means for supporting articles to be fed adjacent the path of movement of the open end of said air duct, an article receiver spaced from said article supporting means and adjacent the path of said peripheral opening, a slide valve intersecting said air duct, means for engaging said slide valve to move said valve into position to connect the open end

of said air duct with said exhaust means when said open end is adjacent said article supporting means, and means for moving said slide valve into another position to connect the open end of said air duct with atmosphere when said open end is adjacent said receiving means.

35. Feeding mechanism comprising a rotary drum having a suction chamber therein, a conduit extending through the axis of said drum for exhausting air from said suction chamber, said drum having a plurality of flanges thereon and having radially extending air ducts connecting said suction chamber with the peripheries of said flanges, a longitudinally extending slide valve interesting a plurality of air ducts, means for supporting articles adjacent the peripheral openings of said air ducts, receiving means arranged adjacent the peripheries of said flanges, means for moving said valve in one direction when the openings of said air ducts are adjacent the article supporting means, and means for moving said valve in the opposite direction when the openings of said air ducts are adjacent the article receiving means.

36. The combination with a rotary carrier having an air duct provided with a peripheral opening for holding an article against the periphery of said carrier, of a pair of spaced guides adjacent said carrier in position to permit an article to be moved by said carrier between said guides, said guides having shoulders thereon for engaging said article when said article reaches its discharge position.

37. The combination with a rotary carrier having an air duct provided with a peripheral opening, of a conveyer having pockets therein, mechanism for moving said conveyer adjacent said carrier and for bringing said conveyer to rest with the pockets therein in registration with said carrier, a pair of guides disposed at opposite sides of said carrier for directing an article on said carrier into registration with a pocket on said conveyer, said guides having shoulders for disengaging said article from said carrier, and means for connecting said air duct with atmosphere when an article on said carrier is in position to engage said shoulders.

38. The combination with a conveyer having a plurality of pockets therein, of a rotary carrier having spaced suction means for holding articles on the periphery thereof, said rotary carrier being movable to position each of a plurality of said suction means over a corresponding pocket in said conveyer and means for moving said conveyer relative to said rotary carrier to bring the pockets under said suction means successively into registration with said suction holding means.

39. The combination with a conveyer hav-

ing pockets thereon, of a drum having a plurality of longitudinally spaced suction means for holding articles against the surface of said drum, means for moving said carrier to bring 5 the pockets thereon successively into registration with said holding means, and means for disengaging the articles from said drum to deposit articles from each of said holding means in various pockets on said carrier as 10 said carrier is moved from one to the other of said holding means.

40. In combination, a magazine for supporting a series of articles on top of one another, a member having a suction opening 15 therein arranged to rotate adjacent the bottom of said magazine for extracting articles therefrom, and a detent arranged at the side of said magazine where said suction opening moves away from said magazine for limiting 20 the number of articles extracted at one time from said magazine by said suction opening.

41. Feeding mechanism comprising a rotary member having a plurality of air ducts therein spaced from one another in the direction of the axis of rotation of said member, and a common valve disposed eccentrically 25 of the axis of rotation of said member for controlling said air ducts.

42. Feeding mechanism comprising a rotary member having a plurality of suction chambers therein, an exhaust device adjustable for exhausting air from one or more of said chambers, said member having air ducts therein connecting said chambers with suction 30 openings equally spaced from the axis of rotation of said member, means for supplying articles to said suction openings, a slide valve intersecting said air ducts, and cam devices at opposite ends of said member for 35 alternately moving said slide valve in opposite directions.

43. The combination with a conveyer having a plurality of pockets therein, of a rotary carrier having spaced suction means for 45 holding articles, said rotary carrier being movable to position each of a plurality of said suction means over a corresponding article receiving area on said conveyer, means for moving said conveyer relative to said rotary carrier to bring said article receiving 50 areas on said conveyer under said suction

means successively into registration with said spaced suction means.

44. In combination, a magazine for containing articles to be fed, a rotary carrier 55 having a suction device thereon for extracting articles at the lower end of said magazine, means for lifting all the articles in said magazine, a contact member associated with said magazine for engaging the articles at a 60 predetermined position to retain the articles above and release the articles below said position, means for operating said contact member to release the same while the articles are being moved relatively to said magazine and 65 for re-engaging said articles to release the lowermost articles and hold the remainder of the articles in position in said magazine, and means for operating said suction device and rotary carrier to extract the lowermost 70 released articles from said magazine.

45. In combination, a series of inclined magazines, a rotary carrier at the bottom of the magazines for extracting articles from said magazines, means upon which the articles are deposited by said carrier in position to form stacks, and means for moving the stacks from one position to another to deposit on each stack an article from more 75 than one of said magazines. 80

46. In combination, a series of magazines, a rotary carrier having a plurality of circumferentially arranged suction devices for extracting articles from each of said magazines, means upon which the articles are deposited by said carrier in separated positions 85 to form stacks, and means for moving the stacks to deposit on each stack an article from more than one of said magazines. 85

47. In combination, a series of magazines, 90 a rotary carrier having a plurality of circumferentially arranged suction devices for extracting articles from each of said magazines and depositing them in a row, means upon which said row of articles are deposited 95 by said carrier to form stacks, and means for moving each of said stacks to receive an article from more than one of said magazines.

In testimony whereof I have signed my name to this specification on this 30th day 100 of October, A. D. 1925.

MICHAEL J. MILMOE.
